WILLIAM J. MANKER AND ALLEN T. MANKER, OF INDIANAPOLIS,
INDIANA.

Letters Patent No. 88,969, dated April 13, 1869.

IMPROVEMENT IN SASH-STOP.

The Schedule referred to in these Letters Patent and making part of the same.

To all whom it may concern:

Be it known that we, WILLIAM J. MANKER and ALLEN T. MANKER, both of Indianapolis, in the county of Marion, and State of Indiana, have invented a new and improved Mode of Supporting Window-Sashes; and we do hereby declare that the following is a full, clear, and exact description of the same, reference being had to the accompanying drawings, forming part of this specification, and in which—

Figure 1 is an interior view of a window with our improvement applied thereto;

Figure 2 is a modification of spring-balance shown in fig. 1, but not forming, by itself, our invention; and

Figure 3 is an enlarged view of the cam-lever shown in fig. 1.

In the drawings—

A is the frame, B, the sash, and C, the stop of a common window.

The sashes, both upper and lower, are hung by a cord, in the usual manner, that is wound upon a drum, E, contained in a box, F, which may be made, of cast-iron, in any convenient or practicable manner, one of which is let into each side of the frame, near the top, for the upper sash, and one on each side, near the meeting rail, for the lower sash.

The drum E is fixed upon a shaft, to which the inner end of the coiled spring G is attached, the outer end of the spring being attached to the box.

In hanging the sashes, the cord D is wound upon the drum E, so that, in drawing out the cord, to attach it to the sash, the spring will be wound up sufficiently

for the tension to counterbalance their weight, when used in connection with the cam-lever or stop herein-after referred to.

In this way, also, the same-size spring may be adapted to different weight of sash.

In connection with these is used the cam-lever L, which serves to support the sash, or sashes, when two are used, in any desired position.

This cam-lever is pivoted, at n, to the sash, and is operated by the handle I.

Rubber or other elastic material is inserted, or otherwise fastened to the end of the lever, at K, which, when pressed against the strip C, by the action of a spiral spring, P, creates sufficient friction to sustain the window at any desired height.

The spring P is coiled in a box, S, which, being secured, or forming part of the plate T, is secured to the window-frame, by means of screws, which hold such plate firmly in position.

Having now described our invention,

What we claim, and desire to secure by Letters Patent, is—

The combination and arrangement of the spring G, drum F, and cord D, with the spring-lever cam L, all constructed and arranged as and for the purposes set forth.

W. J. MANKER.
A. T. MANKER.
